Inventor
By G. W. Stevenson at

UNITED STATES PATENT OFFICE.

HENRY W. MANSUR, OF BOSTON, MASSACHUSETTS.

HOPPER WATER-CLOSET.

SPECIFICATION forming part of Letters Patent No. 311,342, dated January 27, 1885.

Application filed April 15, 1884. (No model.)

To all whom it may concern:

Be it known that I, HENRY W. MANSUR, a citizen of the United States, residing in the city of Boston, in the county of Suffolk and

5 State of Massachusetts, have invented certain new and useful Improvements in Hopper Water-Closets, of which the following is a specification.

This invention has relation to improvements 10 in hopper water-closets; and it consists in the construction and novel arrangement of devices, as will be hereinafter more fully set forth, and particularly pointed out in the claim appended.

15 To enable others skilled in the art to which my invention relates to make and use my improvements, I will proceed to describe the same, referring to the accompanying drawings, which form part of this specification, and in 20 which—

Figure 1 is a longitudinal vertical section of a hopper water-closet embodying my invention. Fig. 2 is a plan view of the same, partly in section, to show the waste-pipe.

25 In Fig. 1, A is the body of the hopper water-closet.

B B is the flushing-rim, and is set or constructed so that there shall be a slight elevation of the front above the rear of the rim to 30 insure the drainage of all water from the rim into the inlet arm or joint D.

C is the curtain or veil overhanging the flushing-rim B B, curving toward and approaching within about half an inch of the interior wall of the hopper.

35 D is the inlet arm or joint connecting the hopper with the supply-pipe on a line, or nearly so, with the flushing-rim.

E is a waste or drain pipe extending from 40 the bottom of the inlet arm or joint D down to and connecting with the outlet of the hopper near its base. When a ventilating-pipe, F, is used, the waste or drain pipe E is connected with upper part of the junction formed

45 by the ventilating-pipe F with the body of the hopper. The waste or drain pipe E dis-

charges all water remaining in the flushing-rim B B and the inlet arm or joint D, after use, into the outlet G of the hopper.

G is the outlet of the hopper.

I is a support forming part of the body of the hopper, and H is a flange at the base of the hopper.

The rim of the bowl of my hopper water-closet is elliptical in form. The inlet of the 55 hopper is at the rear of the ellipse. The inner surface of the bowl of the hopper at the rear is nearly perpendicular and nearly in line with the outlet of the hopper, while the inner surface of the front and sides of the bowl of 60 the hopper slope uniformly, so as to preserve a uniform proportional ellipse from the rim of the bowl to a point nearly vertical with the perpendicular line of the outlet of the hopper. This point is about three inches from the base. 65

The practical operation of the hopper water-closet is that the water from the supply-pipe is driven over both sides of the surface of the bowl, and meeting at the front is gathered into one volume and projected in a body against 70 the rear wall of the hopper, and nearly vertically into the outlet, so as to insure a thorough drenching and washing of the hopper and the removal of any soil that may have been deposited in the mouth of the ventilating-pipe F.

Having fully described my invention, what I desire to secure by Letters Patent is—

In a hopper water-closet having inlet-pipe D, the bowl A, constructed as described, having the forward portion of the flushing-rim 80 slightly elevated, and the skirt-flange overhanging the same, combined with a vertical waste-pipe, E, extending from the base of said inlet-pipe at its point of junction with the bowl to the discharge-opening thereof, substantially as specified.

HENRY W. MANSUR.
